(57) **CLAIM**

We claim the ornamental design for an LED universal mount with integrated LEDs, as shown and described.

DESCRIPTION

FIG. 1 is an isometric view of an LED universal mount with integrated LEDs;

FIG. 2 is front elevation thereof;

FIG. 3 is a right elevation thereof;

FIG. 4 is a top plan view thereof;

FIG. 5 is a bottom plan view thereof; and,

FIG. 6 is an isometric view of two LED universal mounts with integrated LEDs, each electrically connected to other. The left elevation is the same as the right elevation and the rear elevation is the same as the front elevation. The structures shown in dashed line form no part of the claimed design.
